MACHINE FOR FILLING FOLDABLE CONTAINERS

Henry James Dolman, James Ian Hamilton, and John Arthur Stewart Ball, Bristol, England, assignors to Brecknell Dolman & Rogers Limited, Bristol, England, a British company

Application May 21, 1956, Serial No. 586,071

18 Claims. (Cl. 53—126)

This invention relates to a machine for closing and sealing foldable containers filled with flowable substances, especially substances in granulated, powdered, shredded or similar flowable form.

The machine is especially, but not exclusively applicable for performing operations on paper bags after filling with sugar, to effect sealing of the filled bags and, by way of example, this particular application of the invention will be more particularly described.

The main operations contemplated after feeding a bag to bag filling means, consist of: filling the bag; folding over the walls of the bag above the level of the substance delivered thereto; and adhesively securing the folded portion to the body of the bag.

Other operations are generally necessary, according to the nature of the substance being packed and the kind of bag employed, and in the case of packing sugar in paper bags, some or all the following operations may be performed in a machine according to this invention, namely—settling or compacting the substance delivered into the bag; tucking inwards gussets in opposite side wall portions of the bag along precreased lines; applying pressure at the top front and rear to form firm “shoulders” on the bagged substance, whilst supporting front and rear bag wall portions to retain the side tucks; trimming off surplus paper adjacent the now-closed mouth of the bag; cross-creasing the front and rear bag wall portions above the formed shoulders; folding upon itself the part of the bag above the cross crease, in one or more stages to form a flap; applying adhesive to the folded over flap; applying pressure to secure firm adhesion of the folded flap to the body of the bag, and drying the adhesive.

Each of the above mentioned operations has been performed previously in the process of packing a flowable material, such as sugar, into a paper bag, but the means available for the performance of these operations has been such that, generally speaking, each operation after feeding a bag to a filling unit, and filling the bag, has, of necessity, been performed while the bag was stationary.

Machines which perform several of the operations listed are known but the movement of the bag through the machine has usually been intermittent, with consequent slowing of the overall operational speed.

The present invention is characterised in that it makes provision for all of the above mentioned operations, after bag filling, to be performed while the bag is continuously moving, even during those operations in which action is taken at opposite sides of the bag in the direction of continuous traverse of the bag. As a result the overall operational speed of the process can be very much increased as compared with the highest speeds obtainable hitherto in processes where the bags move intermittently.

The bag feeding and bag filling operations need not form part of the machine provided by the present invention, though, for convenience, bag feeding and bag filling units are incorporated in a machine which embodies

2

means for the performance of the remaining operations. In the machine to be hereinafter described the bag filling operation is effected while a bag is held stationary, but thereafter the filled bag moves continuously and substantially uniformly, while the remaining operations are performed. The last operation mentioned, that is, the operation which consists in drying the applied adhesive, is, of necessity, performed at a much slower speed than that at which the bags move during the performance of bag sealing operations, so that whilst these last-mentioned operations are performed on individual filled bags moving at a comparatively high speed, it is necessary for a number of filled and sealed bags to be simultaneously the subjects of the adhesive drying operation.

Briefly the invention provides means for continuously traversing foldable containers filled with a flowable solid substance (such as paper bags filled with sugar) along a predetermined path at a substantially uniform speed and means operating synchronously with the moving containers for performing on each container in succession the operations necessary to seal the containers, such as folding over part of the walls of the container above the level of the substance contained therein and adhesively securing the folded portion to the body of the container to produce a sealed package. Provision may be and preferably is also made for the performance of supplementary operations, such as already referred to above.

In a preferred arrangement a continuously moving endless conveyor is employed, arranged, for instance, as a closed oval in plan, so that a substantially continuous horizontal supporting surface is provided for the containers to be sealed. In such a case certain operations may be performed along one side of the oval shaped conveyor, such as feeding bags to filling means and delivering filled bags to the conveyor, whilst operations concerned with the sealing of the filled bags are performed in a row of units on the other side of the oval shaped conveyor.

A machine for sealing bags of sugar to be hereinafter described, by way of example, embodies a number of units possessing per se novel features of construction and operation and these units operating synchronously on successive bags provides also a novel mechanism combination.

The accompanying drawings illustrate diagrammatically, and by way of example, the operations to be performed on a continuously moving bag of sugar and the basic mechanical actions required for the performance of these operations. In the drawings:

Figure 1 illustrates by a series of diagrams some of the operations performed by the machine to be described,

The machine diagrammatically illustrated in Figure 2 comprises a horizontal endless conveyor of elongated oval form in plan so that all parts of the conveyor lie at substantially the same level. This feeding conveyor comprises a plurality of carrier units articulately interconnected by pivoted links to form in effect an endless chain structure.

Each carrier unit 1 (Figures 3, 4 and 5) comprises a sectional holder 2 in opposite ends of which are journalled for free rotation rollers 3 revolving about horizontal axles 4 and adapted to roll along the top edge of a continuous fixed guide rail 5 and upper and lower paired rollers 6, 6A respectively revolving about vertical axles 7 and aligned axles 7A (Figure 5) and adapted to bear upon opposite sides of said guide rail 5 and thus steady the holder 2 as it moves. The guide rail 5 is suitably mounted on the machine frame 200. Movement is imparted to the carrier units 1 through an endless chain 8, the pivot pins of some of the chain links being removed and replaced by pairs of pegs 9 upstanding from slide blocks 10 mounted for free lateral sliding movement each within a slot 11 in the holder 2 on paired pins 12 transversely spanning said slot. The permitted lateral movement of the slide blocks 10 compensates for the slight variation in the relative disposition of the chain 8 and holder 2 which takes place when traversing an arcuate path around sprocket 13. The chain 8 is driven continuously by sprocket wheels 13 rotatably mounted on machine frame 200 (Figure 2) and suitably driven by known power means (not shown). The gaps between adjacent holders 2 are closed by fence means 14, comprised in part by wide springy blades, mainly to guard against material being packed adhering to the rail 5.

The carrier unit 1 is provided with a pocket 15 open at top and bottom and at the front and constituted by a normally fixed but detachable back plate 16, an independently adjustable rear wall or jaw 17A and a flap-like jaw 17 which forms the front end of the sprocket and is supported by a pivot 18 mounted on a bracket 19 secured to the holder 2. A tension spring 20, is connected by a chain 20A to an arcuate anchorage 18A secured to pivot 18, and normally holds the jaw 17 in the closed position. Secured to the jaw pivot 18 is a lever 21 which carries a roller 22 adapted at appropriate times to contact with a fixed cam track (not shown) and effect a swing-open movement of the jaw 17 to varying extents according to requirements. As long as the machine is in operation the chain-linked carrier units circulate uniformly through an

endless path under power derived through one or other of the chain sprocket wheels 13 provided at opposite ends of the machine frame 200. This circulatory motion repeatedly brings the carrier units 1 back into line with bag filling means.

Bag filling means of any suitable construction may be employed provided the filling operation performed terminates in depositing a filled bag on a horizontal platform 200A from which it can be displaced into the pocket of a moving carrier unit 1. Accordingly in Figure 2 alone there is given a diagrammatic representation of bag filling means, that is, a bag magazine 23 and a filler spout 24, the position of a bag 25A after filling being indicated by a chain-dotted rectangle.

Because the time taken by the longest operation performed on a filled bag may not be more than half that occupied in filling a bag, the bag filling operation can be carried at two or more filler units alternately or simultaneously. If bag filling takes place at the two filler units simultaneously, as here supposed, the two filled bags 25A are simultaneously pushed by reciprocatory paddles (not shown) from off platforms on to which the bags have been delivered from beneath the filler spouts, so as to transfer the bags into the pockets of two moving carrier units. The two filler units are spaced apart at a distance equal to an odd number of carrier unit pitches, for instance, five pitches apart, so that the filled bags transferred from the filler units, which operate at half the machine speed (that is, half the traverse speed of the carrier units), are placed in alternate carrier unit pockets. Hence the feeding conveyor after passing the second of the filler units has filled bags 25 in each of its successive carrier units.

The filled bags 25 are traversed by chain 8 through two settling units for the purpose of compacting the sugar in the bags as much as possible and thus obtain in each bag a substantially constant contents height. Each settling unit conveniently consists of a vibrating endless belt 26 over which the bags move and a travelling guide belt 26A which lies opposed to the fixed back plate 16 of a carrier pocket 15 travelling past said belt. The settling units may be arranged, as shown, at opposite ends of one end bend of the conveyor.

The various units provided by this invention for sealing bags after settling of the contents thereof are conveniently disposed in line on the return side of the conveyor, as indicated in Figure 2.

After contents-settling in units 26 the first operation on the filled bag 25 is that of tucking in the gussets 27, 27A of the bag (A—Figure 1), which has been precreased to facilitate this operation. The filled bag 25 is slid over a fixed supporting ledge track 28 mounted on machine frame 200 and comprising a series of laterally spaced horizontal rails (see especially Figure 15) by the carrier unit 1 in whose pocket 15 it is lightly gripped between the angle-shaped fixed jaw 17A and the biased flap-like jaws 17, to a tucker unit 29 (see Figures 6, 7, 8 and 9). One of the gussetted sides of the bag 25 (i.e. gusset 27) faces the direction of traverse, which is always indicated where possible, by arrow A. The tucker unit 29 comprises front and rear vertically reciprocating tucker fingers 30, 31 respectively, of which the former, that is, the front tucker finger 30, is adapted to be lowered by a parallel linkage device into the path of the oncoming bag 25. The parallel linkage device comprises a pair of equal length arms 32 secured to parallel pivots 32A mounted on a vertically slidable block 32B connected by links 32C to a lever 32D rockable on a fixed pivot 32E and operable by a cam 32F on a rotatable main shaft 201; the front tucker finger 30 constitutes an extension of a bar 30A pivoted to arms 32 by pins 30B. The bag is allowed to press against the descending front tucker finger 30 thereby forcing the front gusset 27 of the bag inwards. Simultaneously the rear

tucker finger 31 is lowered behind the bag by means of another parallel linkage device comprising a pair of interconnected rotating arms 33 of equal length arranged so that the rear tucker finger 31 overtakes the bag 25 and forces its rear gusset 27A inwards, as diagrammatically represented at A, Figure 1.

The arms 33 are secured to parallel shafts 33A connected through toothed gearing 33B to a power driven shaft 33C in such manner that both shafts 33A rotate in the same direction, shaft 33C being rotated through bevel gearing 33D from the same main shaft 201 on which front tucker cam 32F is carried; the rear tucker finger 31 constitutes an extension of a bar 31A pivoted to arms 33 by pins 31B.

While the front and rear tucker fingers 30, 31 are inserting the gussets in the moving bag 25 the tendency for the upper parts of the front and rear walls of the bag to close together during the gusset-tucking operation is assisted by a pair of swinging plates 34 having lower edges constituted by freely revolving rollers 35. The swinging plates 34 are moved by means of meshing toothed sectors 36 keyed to a pair of parallel shafts 36A, 36B mounted in brackets 136A, 136B secured to machine frame 200; the plates 34 with associated rollers 35 are carried by arms 36C secured to shafts 36A, 36B and move in unison by reason of pivoted tie rod 36D extending between arms 36E, 36F, also secured to shafts 36A, 36B. A rocking motion is imparted to plates 34 and rollers 35 by cam-operated linkage, synchronously with the reciprocatory movements of the front and rear tucker fingers 30, 31, said linkage comprising a connecting rod 37A pivoted to arm 36E and to a bell crank lever 37B mounted on pivot 37C and cooperating with a cam 37D on shaft 201. This bag closing operation is diagrammatically represented at B, Figure 1 and the mechanism employed in Figures 6, 7, 8 and 9.

The next operation is diagrammatically represented at C, Figure 1, and consists in pressing down the sugar in the bag, whilst maintaining a grip on the closed-together bag walls 38, in order to form square shoulders. The means employed for this operation are two similar former shoes 39 between which the closed-together upper walls 38 of the bag are received and loosely supported. The former shoes 39 are vertically adjustably mounted on the depending limbs of bifurcated yokes 40 (Figure 10) each articulately carried by a parallel linkage 41 including pairs of rocker arms through which a vertical reciprocatory motion is imparted to the suspended former shoes 39. This gripping of the bag walls 38 while this pressing or contents-forming operation takes place is effected by means of opposed spring-loaded plungers 42 carried by a pair of parallel carrier bars 43 which are operated at a constant speed, synchronously with the pre-arranged speed of operation of the machine, with a horizontal rotary motion derived from revolving arms 44 at opposite ends of the carrier bars. The two arms 44 at each end of the mechanism are pinned to parallel vertical shafts 44A, 44A' carrying elements of a gear train 44B adapted to rotate the arms in the same direction, driving motion for one of said shafts (44A) at one end being derived through bevel gearing 44C from a drive shaft 44D rotated from any suitable power source. Bevel gearing, such as 44E and a connecting shaft 44F transmits driving power from shaft 44A at one end of the mechanism to an equivalent shaft at the other end. The carrier bars 43 serve also in the performance of the next operation. The parallel linkage 41 by means of which the former shoes 39 are operated includes also spring connections 45 which allow the yokes 40 to collapse, thereby permitting the rocker arms of the linkage to continue their full swing while the shoes 39 are pressed firmly on the bag and its contents. The spring-loaded plungers 42 are adapted, as the carrier bars 43 advance toward one another, to grip the bag walls 38

for a suitable period of time, for instance, that equivalent to 40° each side of the inner dead centre of the revolving arms 44 on which the carrier bars 43 are mounted. During this period the carrier bars 43 move with the bag 25 at approximately the same speed and this ensures that the upper part 38 of the bag is not pulled backwards when the former shoes 39 operate. While the bag is gripped by the plungers 42 on the carrier bars 43, the former shoes 39 descend and shape the bag tightly over the top of the contents of the bag, the former shoes 39 rising from the top of the contents before the gripping plungers 42 release the bag as the carrier bars 43 recede from one another.

While the former unit is operating on one bag, the tucker unit can be operating on the following bag and the next operation after forming, that is, creasing and shearing of the bag top, can take place on the preceding bag. As previously mentioned, the carrier bars 43 on which are mounted the bag gripping plungers 42 for use in the forming operation serve also during the creasing and shearing operation which is diagrammatically represented at D, Figure 1. The creasing is effected by means of opposed male and female creasing blocks 46 mounted on the parallel carrier bars 43 and thus having an operational period equal to that of the gripping plungers 42 of the former unit. These creasing blocks 46 not only form a crease across the closed-together upper part of the bag but serve also to grip the bag so that the upper part 38 of the bag is not pulled backwards when surplus material is trimmed off at the closed mouth of the bag. The trimming action is performed by the co-operation of a fixed shear blade 47 and a swingable shear blade 48 (see Figure 12) rockably mounted on pivoted lever means 49 to which a swinging motion is imparted by cam-operated means. These cam-operated means comprise a cam 50A mounted on drive shaft 201, a bell crank lever 50B swingable on a pivot 50C carried by a bracket 200A on the main frame 200, said lever 50B having a follower roller 50D engaging cam 50A, and a length adjustable tie rod 50E pivotally connecting the lever 50B to one of a pair of rockers 49A pinned to a common axle 49B in fixed housing 200B, the blade lever means 49 which are mounted by pivots 49C on rockers 49A being biased by spring 49D toward fixed blade 47 as the toe 49E of one rocker 49A swings from beneath abutment roller 200C on housing 200B.

The trimmed and creased bag is next acted upon by a fixed rail 51 (Figure 13) which progressively turns over the portion of bag material until doubled upon itself to form an upright flap 52; an intermediate and the final stages of this turn-over action are diagrammatically represented at E and F respectively of Figure 1.

The bag 25 is then passed on to a glueing unit where the double-over flap 52 is tilted by a plate 53 into an inclined position (conveniently 45°) in order to pick up glue from a conical glue-transfer roller 54 whilst held in contact therewith by a press roller 55 as diagrammatically represented at G, Figure 1. The press roller 55 is so suspended on an axle 45 (Figure 16) as normally to swing toward the glue-transfer roller 54, but is adapted under the influence of cam-operated linkage 57 to be swung away from the glue-transfer roller 54, as indicated by dotted lines in Figure 16, to allow sufficient space to the ready acceptance between the glue-transfer roller 55 of the tilted flap 52 of a bag 25, the flap tilting plate 53 mounted on the press roller axle 56 and thus swinging therewith. The glue-transfer roller 54 is supplied with glue from an adjustable nozzle 58 fed under pressure through a valve-controlled pipeline 59 from a pump 60. The press roller 55 is caused to apply pressure on the flap 52 after the leading end thereof has moved over the glue-transfer roller 54 and the pressure is removed before the whole of the flap 52 has moved across the glue-transfer roller

54, thereby ensuring that glue is not deposited on the ends of the flap 52.

The conical glue-transfer roller 54 is driven at a peripheral speed which is equivalent to the linear speed of the bag and has two grooves 61 machined into the conical face. The circumferential length of these grooves is less, for instance, by about $\frac{1}{4}$ ", than the length of the bag flap. The pressure supplying glue to the nozzle 58 is variable and when the plain portion of the conical face of the glue-transfer roller 54 is in contact with the nozzle 58 its orifice is completely sealed, but when the grooved portion of the glue-transfer roller 54 rotates past the nozzle 58 the grooves 61 become filled with glue. The press roller 55 has circumferential ribs 62 complementary to the grooves 61 and these ribs 62 press the bag flap 52 onto the grooved glue-transfer roller and causes glue to be transferred from the grooves to the bag flap 52, as the circumferential position of these grooves is synchronised with the feeding movements of the bag. In the event of there being no bag 25 in the glue receiving position, the surplus glue is scraped from the conical face of the glue-transfer roller 54 by a scraper blade 63 and is returned via a collecting cup 64 to a glue reservoir 65. Immediately the bag flap 52 leaves the glue-transfer roller 54, it is deflected by a former plate 66 (Figure 13) over the top of the bag 25 parallel with the contents thereof.

The final operation performed on the bags 25 as they are moved by chain 8 in single file and at uniform speed around the machine is that of applying pressure to the now-flat glued flap 52 in order to cause it to adhere firmly to one of the formed shoulders. This operation is diagrammatically represented at H, Figure 1 and is performed by pressing the flap 52 down to lie on the bag 25 and then passing the flap under a rising and falling pressure plate 67 of a press unit.

The pressure plate 67 of the press unit is carried at each end on a pair of rotating pivotally mounted arms 68, which are biased by spring 69 downwards and are associated with a fixed edge cam 70 for controlling the rising and falling of the pressure plate 67. The bag flap 52 slides under the pressure plate 67 until the rotary arms 68 which operate the plate are at about 40° in advance of the front dead centre position. The arms 68 are allowed by the edge cam 70 to pivot downwards so that the plate 67 is now pressing the glued bag flap 52 hard onto the top of the bag. At this juncture the plate 67 is travelling at approximately the same speed as the bag and continues so to travel until the operating arms 68 have reached a position about 40° behind the front dead centre position. The pressure plate 67 is then lifted by the action of the edge cam 70 to relieve the pressure imposed by plate 67 on the flap 52 by the pivoting arms 68. The bag 25 then slides from under the pressure plate 67 into fixed guides which stop the glued flap and the bag top from springing upwards. The folding and securing of the bag top is now complete. Throughout the traverse of the bags 25 through the machine and particularly between the various operating units the bags are supported and/or guided by suitable rails or the like.

The bag 25 is finally transferred from its carrier unit 1 to a dryer 71 (Figure 2) by means of a conveyor belt 72. The bags 25 issuing from the machine are marshalled into groups of four and each group is then pushed into the dryer 71, which consists of a pair of continuously moving upper and lower belts, the lower belt supporting the bags and the upper belt pressing down onto the top of the sealed bags. The upper belt is pressed down by means of a series of sprung arms and rollers, so that the upper belt firmly holds the flaps on the tops of the bags during the whole of the period they are passing through the dryer. This period is long enough for the glue to dry so that the bags can then be readily handled.

It has already been intimated that the container filling means and the means for transferring filled containers to the continuously moving conveyor means hereinbefore de-

scribed can be known applications. However, by way of example, a suitable mechanism for transferring filled bags of sugar to said conveyor means is illustrated in Figures 20 to 25 inclusive.

5 A bag after being filled, for example, with sugar, drops from the filler spout of a bag filling unit (not shown) on to a bag supporting tab 24 (in this position the bag is designated 25B, Figures 2, 20, 21 and 22). The bag is then transferred to position 25A (Figures 2 and 20) by means of a pusher plate 101 mounted on a pivotally collapsible bracket arm 102, which in turn is mounted on a pillar bracket 103 carried on a slidable shaft 104. The pusher plate 101 and the bracket arm 102 collapse only when there is a positive resistance against their forward motion, due, for example, to a bag falling on its side. Collapsing of bracket arm 102 and pusher plate 101 in relation to the pillar bracket 103, which is being traversed along the shaft 104 as later described, is utilized to operate a switch (not shown) in known manner so that the machine stops automatically.

The forward and return motion of the pillar bracket 103 fixed to slider shaft 104 is effected by means of a barrel cam 105 on a drive shaft 106, through a cam lever 107, links 108, and a collar 109 fixed to shaft 104. After the bag is transferred to position 25A the pillar bracket 103 is rocked to the designated position 25A in Figure 22, by the turning of slider shaft 104. This rocking motion is effected by means of cams 111 on drive shaft 106, cam rockers 112, linkage 113, and guide brackets 114 supported with freedom to rock on and in relation to slider shaft 104. A common guide bar 115 extends between brackets 114 and is slotted to receive a guide roller 116 mounted on a twist lever 110 keyed to shaft 104; the pillar bracket 103 remains in position 103A until the pusher plate 101 carried on said bracket 103 has returned to its retracted position. The pillar bracket 103 is then pivoted inwards to a vertical position to dispose pusher plate 101 behind a bag in position 24.

The bag 25 is then pushed from position 25A on to supporting ledge 28, into a carrier pocket 15 (Figure 2) while it is moving at a continuous uniform speed, the front flap 17 of the pocket being held open in position 17a to receive it, as shown in Figure 20. This bag feeding motion is effected by means of a pusher plate 130 mounted on a slidable rack bar 118 (Figure 22) operated by a gear pinion 119 rolling on a fixed rack 120. A traversing movement is imparted to the gear pinion 119 to cause it to roll on fixed rack 120 by a cam 121 on drive shaft 106, a cranked cam lever 122, an adjustable link 123, paired "giveaway" levers 126, a pivoting shaft 127, an operating lever 128 and a link 129 connected to the axle of gear pinion 119. The so-called "giveaway" levers 126 incorporate means which allow them to collapse if the bag meets any positive resistance as it is pushed into a carrier pocket 15. For example, the pocket 15 thus becomes out of step with the pushers 130 and the machine will be stopped automatically.

It will be appreciated that the pivoted pocket jaw or flap 17 must be made to swing open to varying degrees according to requirements; that is, the jaw is opened wide to receive a bag from a bag feed unit, is opened enough to release the bag in both of the settler units 25 (Figure 2) and is again opened wide to release the bag for transfer to the take-off conveyor 72 (Figure 2).

65 We claim:

1. A machine for closing and sealing foldable bags filled with a flowable substance comprising a substantially horizontal continuous surface of substantially straight-sided oval form in plan, for supporting filled bags, a continuously circulating endless conveyor chain, bag carrier units connected to said chain and each including a pair of relatively swinging jaws for receiving a filled bag along one straight stretch of said surface and for gripping the filled bag therebetween to slide said bag along the two straight stretches and the joining curve of said support-

ing surface, bag-contents settling means and bag closing and sealing mechanisms arranged in appropriate sequence and mounted adjacent the other straight stretch of said supporting surface to operate in succession on bags in the passing carrier units, each of said closing and sealing mechanisms having operating members mechanically advanced toward and traversed in step with said bags by parallel linkage devices moving synchronously with the continuous circulating movement of the conveyor to effect closing and sealing of the bags and also receding from the bags during bag closing and sealing operations without interfering with the movements of the conveyor.

2. In a machine for closing foldable containers wherein continuously circulating means traverse said containers over a substantially horizontal track through closing mechanisms, the employment of a continuous fixed guide rail adjacent said horizontal track, an endless chain continuously traversed adjacent to said guide rail and said track, a plurality of carrier units connected at spaced intervals to said chain, each carrier unit comprising a holder attached to the chain, freely revoluble rollers on said holder for rolling along said guide rail, a lateral jaw fixed on said holder, another lateral jaw pivoted to said holder and normally substantially parallel to said fixed jaw, means biasing said pivoted jaw toward said fixed jaw, and cam track means co-operating with said carrier unit pivoted jaws to effect opening thereof against the influence of said biasing means.

3. In a machine for closing foldable containers wherein continuously circulating means traverse said containers over a substantially horizontal track through closing mechanisms, the employment of a continuous fixed guide rail spaced above and vertically edge-on in relation to said track, an endless chain, means for continuously circulating said chain, in a path above said guide rail, and a plurality of carrier units each comprising a holder embracing said guide rail, freely revoluble rollers mounted within said holder and in rolling contact with the top and sides of said guide rail to guide and support said holder, a block mounted for lateral sliding on said holder and attached to said chain, a fixed jaw mounted on one end of said holder, a vertical pivot mounted at the other end of said holder, a jaw swingably mounted on said pivot, spring means anchored to said holder and to said swingable jaw to bias it toward said fixed jaw and a vertical back plate mounted on said holder between said jaws.

4. In a machine for closing foldable bags containing a flowable solid substance, a fixed substantially horizontal track, continuously circulating means for traversing filled bags along said track, mechanism for tucking-in gussets at opposite sides of open bag tops and comprising a front gusset-engaging vertically suspended finger, linkage for reciprocating said front finger, a rear gusset-engaging vertically suspended finger, parallel linkage for reciprocating said rear finger and for accelerating its advance toward the rear bag gusset so that front and rear fingers travel in step for a limited period, and means for applying pressure to the bag during said period to form square shoulders on the bagged substance.

5. In a machine for closing foldable bags wherein continuously circulating carrier units traverse said bags over a substantially horizontal track through bag closing mechanism, said bags being precreased at opposite sides of the open mouths thereof to facilitate the forming of inwardly folding gussets, the employment of gusset tucking mechanism comprising a front tucker finger, a pair of equal-length arms pivotally connected to said front tucker finger, parallel pivots supporting said arms, a vertically slideable block supporting said pivots, cam means for reciprocating said block, said pivots constituting with said front tucker arms and said front tucker finger, a parallel linkage imparting vertical reciprocation to said suspended front tucker finger to cause it to descend and ascend in relation to the front of a travelling bag to infold a front gusset, a rear tucker finger, a pair of equal-length

arms pivotally connected to said rear tucker finger, parallel shafts supporting and rotating said rear tucker arms and power means for rotating said shafts in the same direction, said shafts constituting with said rear tucker arms

5 and said rear tucker finger a parallel linkage imparting vertical reciprocation to said suspended rear tucker finger to cause it to descend behind the rear of the travelling bag engaging the front tucker finger, to follow-up the bag movement and then to ascend after infolding the rear gusset.

6. In a machine for closing foldable bags containing a flowable solid substance and having continuously circulating means for traversing filled bags over a substantially horizontal track through bag top folding means, the combination with gusset tucking mechanism as claimed in claim 5, of mechanism for forming square shoulders on the bagged substance and for conforming the foldable bag tops thereto, said mechanism comprising interconnected parallel shafts, means for rocking the interconnected shafts, pressure plates depending from said shafts and moving into and out of gripping contact with the top of one bag passing therebetween and rollers on the lower ends of said pressure plates for forming shoulders on the bagged substance and synchronously operated means for consolidating the formed shoulders and comprising a pair of former shoes spaced laterally to admit of passage therebetween of the pressed-together top walls of another bag which has been subjected to the forming action of said plates and rollers, a yoke supporting said former shoes and parallel motion linkage comprising power-rocked levers, links pivoted to said levers and said yoke to impart vertical reciprocation to the former shoes, collapsing of the links as said levers complete a predetermined rocking stroke ensuring firm pressures on the bag shoulders by said former shoes.

7. In a machine for closing foldable bags having continuously circulating means for traversing filled bags in a substantially horizontal plane, mechanism operating on a travelling bag prior to sealing the open mouth of the bag, comprising parallel carrier bars, means for moving said bars toward and away from the foldable top of the bag with a horizontal rotary motion, plungers on said carrier bars for gripping said foldable bag top, co-operating blocks for creasing said bag top to facilitate folding and cutting blades for trimming surplus material from the bag top.

8. A machine for closing foldable bags containing a flowable solid substance, comprising a horizontal continuous ledge for supporting filled bags, an articulated conveyor circulating adjacent said ledge, bag carriers secured in spaced relation to said conveyor to move therewith, front and rear fingers mounted adjacent said ledge and conveyor and vertically reciprocated by separate parallel linkage devices for tucking-in gussets at opposite sides of a travelling bag, carrier bars in series with said gusset tucking fingers and shoulder forming means movable toward and away from another travelling bag with a horizontal rotary motion, swinging pressure means for applying pressure to the open bag tops to form square shoulders therein, said carrier bars supporting plungers for gripping said foldable bag tops in succession during shoulder forming, co-operating blocks for creasing said bag tops to facilitate folding and cutting blades for trimming surplus material from the bag tops.

9. In a machine for closing foldable bags having continuously circulating means for traversing filled bags over a substantially horizontal track through bag closing mechanism, the employment of means for cross creasing and trimming the tops of filled bags prior to fold-closing said tops, comprising two longitudinally spaced-apart pairs of vertical shafts also equidistantly spaced laterally, equal length arms on the lower ends of said shafts, power-operated means for rotating said shafts, a pair of carrier bars pivotally mounted on said arms and caused thereby to perform horizontal movements in phase with bag traverse to advance said bars toward and recede them

from upstanding tops of bags being traversed over said horizontal track, inwardly directed plungers on said carrier bars set in opposed pairs, spring means biasing said plungers toward the moving bags to grip said bag tops therebetween, a longitudinal male crease-forming block on one carrier bar, a complementary female crease-forming block on the other carrier bar, a first bag-top trimming blade fixed in relation to said bag track, a second bag-top trimming blade for co-operating with said first blade and cam-operated linkage imparting timed swinging movement to said second blade to trim the top of a travelling bag as the bag top is held by the moving creasing blocks.

10. In a machine for folding-down and sealing the tops of bags traversed by continuously circulating means over a substantially horizontal track, the employment of means for adhesively sealing said tops to the bag bodies comprising a turn-over rail fixed in relation to said track to progressively turn over upon themselves the laterally flattened bag top walls, a conical glue transfer roller mounted for rotation about a vertical axis above said track, a nozzle mounted adjacent said transfer roller to feed glue thereonto, a fixed glue reservoir, means for pumping glue from said reservoir to said feed nozzle, a press roller mounted adjacent said transfer roller for intermittent movement toward and away from said transfer roller for pressing a folded bag top flap onto said transfer roller, and means for pressing the glued flap against the body of the bag to cause it to adhere thereto.

11. A machine for closing and sealing foldable containers, comprising a fixed substantially horizontal continuous ledge for supporting containers to be closed and sealed, a continuously circulating endless conveyor comprising a plurality of articulately connected pockets each for receiving and gripping a container for traversing it over said supporting ledge, container closing and sealing mechanisms arranged in appropriate sequence and mounted adjacent said supporting ledge to operate in succession on containers in the passing conveyor pockets, said closing mechanisms comprising bag top gusset tucking fingers and shoulder formers and vertically disposed parallel linkages drivingly connected thereto, and further comprising a bag top gripping and creasing means and horizontally disposed parallel linkages drivingly connected thereto to cause said fingers and formers, and said gripping and creasing means to advance toward, to travel with and to recede from said bags synchronously with the continuous circulating movement of the conveyor to effect closing of the bags, and said sealing mechanisms comprising rotary gum applying means, bag top folding means and vertically reciprocating pressure means operating to seal said bags, thereby closing and sealing said bags without interfering with the constant rate of travel thereof, as said bags are traversed by the continuous circulating conveyor.

12. A machine as claimed in claim 11, wherein said continuously circulating endless conveyor comprises a plurality of bag carrier units articulately interconnected by chain links, each carrier unit including a pair of relatively movable jaws for embracing a filled bag for sliding it over said supporting ledge.

13. A machine for closing and sealing foldable bags, comprising a fixed substantially horizontal continuous ledge of substantially straight-sided oval form in plan, for supporting filled bags, a continuously circulating endless conveyor comprising a plurality of articulately connected pockets each for receiving a filled bag along one straight stretch of said ledge and gripping it for sliding said bag over the two straight stretches and the joining curve of said supporting ledge, bag-contents settling means and bag closing and sealing mechanisms arranged in appropriate sequence and mounted adjacent the other straight stretch of said supporting ledge to operate in succession on bags in the passing conveyor pockets, said closing mechanism comprising bag top gusset tucking

5 fingers and shoulder formers and vertically disposed parallel linkages drivingly connected thereto, and further comprising bag top gripping and creasing means and horizontally disposed parallel linkages drivingly connected thereto to cause said fingers and formers and said gripping and creasing means to advance toward, to travel with and to recede from said bags synchronously with the continuous circulating movement of the conveyor to effect closing of the bags, and said sealing mechanisms comprising rotary gum applying means, bag top folding means and vertically reciprocating pressure means operating to seal said bags, thereby closing and sealing said bags without interfering with the constant rate of travel thereof as said bags are traversed by the continuous circulating conveyor.

10 14. A machine as claimed in claim 11, including bag top trimming means comprising relatively movable shear blades and cam control mechanism therefor to effect trimming of a bag top while held by said gripping and creasing means.

15. In a machine for closing filled open top gusseted bags with a flowable substance, a fixed substantially horizontal continuous track, means continuously and unidirectionally moving filled bags along said track, 25 tucker fingers spaced apart in the direction of movement of said bags, parallel linkage supporting said fingers and performing orbital movements in a plane perpendicular to the path of movement of said bags, so that one descending finger successively contacts the gusseted front side of a moving bag and the other descending finger successively follows up the gusseted rear side of the same bag, presser elements to close together the upper parts of the front and rear walls of each bag during the gusset-tucking operation, means for moving said 30 presser elements laterally toward and away from successive bags, first means for applying pressure on each bag to form firm shoulders on the bagged substance, said first means comprising a pair of vertically reciprocated shoes applying forming pressure on opposite sides of the closed-together upper walls of the bag, and second means for supporting front and rear wall portions of each bag during the shoulder forming operation thereon to retain the front and rear tucks in position, said second means comprising plungers supported on parallel carrier bars which advance laterally toward and recede from the bags in succession and move synchronously with the continuously and unidirectionally moving bags.

40 16. In a machine for closing filled open top gusseted bags with a flowable substance, a fixed substantially horizontal continuous track, means continuously and unidirectionally moving filled bags along said track, tucker fingers spaced apart in the direction of movement of said bags, parallel linkage supporting said fingers and performing orbital movements in a plane perpendicular to the path of movement of said bags, so

45 that one descending finger successively contacts the gusseted front side of a moving bag and the other descending finger successively follows up the gusseted rear side of the same bag, presser elements to close together the upper parts of the front and rear walls of each bag during the gusset-tucking operation, means for moving said presser elements laterally toward and away from successive bags, a pair of vertically reciprocated shoes for applying pressure on opposite sides of the closed-together upper walls of each bag to form firm shoulders on the bagged substance, a pair of parallel carrier bars between which the partly closed bags move, horizontally disposed parallel linkage to cause said carrier bars to advance toward, to travel with and to recede from said bags, synchronously with the continuously and unidirectionally moving bags,

50 17. In a machine for closing filled open top gusseted bags with a flowable substance, a fixed substantially horizontal continuous track, means continuously and unidirectionally moving filled bags along said track, tucker fingers spaced apart in the direction of movement of said bags, parallel linkage supporting said fingers and performing orbital movements in a plane perpendicular to the path of movement of said bags, so that one descending finger successively contacts the gusseted front side of a moving bag and the other descending finger successively follows up the gusseted rear side of the same bag, presser elements to close together the upper parts of the front and rear walls of each bag during the gusset-tucking operation, means for moving said presser elements laterally toward and away from successive bags, a pair of vertically reciprocated shoes for applying pressure on opposite sides of the closed-together upper walls of each bag to form firm shoulders on the bagged substance, a pair of parallel carrier bars between which the partly closed bags move, horizontally disposed parallel linkage to cause said carrier bars to advance toward, to travel with and to recede from said bags, synchronously with the continuously and unidirectionally moving bags, resilient plungers on said carrier bars for supporting closed-together front and rear wall portions of each bag during the shoulder forming operation thereon to retain the front and rear tucks in position, opposed male and female creasing blocks on said carrier bars for

cross-creasing the closed-together bag tops, and bag top trimming means operating synchronously with bag movement and simultaneously with the cross-creasing operation on each bag.

17. In a machine having mechanism for closing bags filled with a flowable substance, a fixed substantially horizontal continuous track, a fixed guide rail above and parallel to said track and a continuously moving endless conveyor for sliding bags along said track, said conveyor comprising a plurality of carrier units articulately interconnected by pivoted links, each carrier unit including a body portion supporting relatively movable jaws for gripping a bag for sliding it along said track, one of said jaws being swingable on said body portion, spring means biasing said swingable jaw to the bag gripping position, and horizontal and vertical rollers on said body portion for engaging the upper edge and side faces respectively of said guide rail, in combination with means alongside said track for swinging said swingable jaw against the resistance of said spring means to release the gripped bag.

18. In a machine for closing bags filled with a flow-

able substance, a fixed substantially horizontal track, conveyor means for continuously moving filled bags unidirectionally along said track, and comprising interlinked carrier units having jaws for gripping bags as they move along said track, a vibrating endless belt constituting part of said track for vibrating the moving bags to settle the contents thereof before bag closing and a travelling guide belt flanking the bags as they are carried along by said vibrating belt to retain said bags between the carrier unit jaws.
